UNITED STATES PATENT OFFICE.

PETER WIEDERER, OF STAPLETON, NEW YORK.

DESIGN FOR A MIRROR-FRAME.

SPECIFICATION forming part of Design No. 23,024, dated January 30, 1894.

Application filed December 26, 1893. Serial No. 494,805. Term of patent 3½ years.

To all whom it may concern:

Be it known that I, PETER WIEDERER, a citizen of the United States, and a resident of Stapleton, in the county of Richmond, in the State of New York, have invented and produced a new and original Design for Mirror-Frames, of which the following is a specification, reference being had to the accompanying drawing, showing a face view of my new and original design for mirror-frames.

The essential features of my design for a mirror frame consist of a ring or frame proper, the arms and head of a clown at the top of the ring and a drum beater held in one hand of the clown and projecting into the ring and the clown's legs at the bottom of the ring.

In the drawing, A is the frame proper.

B represents the head of a clown at the top

of the frame; C the arms of the clown embracing the top of the frame.

D is a padded drum-stick in one hand of the clown, and E are the legs of the clown at the bottom of the frame.

Having thus described my invention, I claim as new and desire to secure by Letters Patent—

The design for a frame, substantially as herein shown and described.

In testimony that I claim the foregoing as my invention I have signed my name in presence of two subscribing witnesses.

PETER WIEDERER.

Witnesses:

OSCAR F. GUNZ,
K. R. BRENNAN.
